UNITED STATES PATENT OFFICE

134,722

DESIGN FOR A COMPASS

George Penza, Detroit, Mich.

Application April 23, 1942, Serial No. 106,673

Term of patent 14 years

To all whom it may concern:

Be it shown that I, George Penza, a citizen of the United States and a resident of Detroit, in the county of Wayne and State of Michigan, have invented a new, original, and ornamental Design for a Compass, of which the following is a specification, reference being had to the drawing forming a part thereof, in which:

Fig. 1 is a front elevational view of a compass in closed position, showing my new design.

Fig. 2 is a front elevational view thereof, with the compass shown in open position.

Fig. 3 is a side elevational view thereof.

Fig. 4 is a sectional view taken on line 4—4 of Fig. 1, on an enlarged scale.

What I claim is:

The ornamental design for a compass, as shown.

GEORGE PENZA.
